US0D1001097S

(12) **United States Design Patent** (10) **Patent No.:** **US D1,001,097 S**
(45) **Date of Patent:** **** Oct. 10, 2023**

(54) **CONTROLLER**

(71) Applicant: **Zhejiang Yuzihe Technology Co., Ltd.**,
Hangzhou (CN)

(72) Inventor: **Jianhao Fang**, Ningbo (CN)

(73) Assignee: **Zhejiang Yuzihe Technology Co., Ltd.**,
Hangzhou (CN)

(**) Term: **15 Years**

(21) Appl. No.: **29/871,795**

(22) Filed: **Feb. 28, 2023**

(30) **Foreign Application Priority Data**

Aug. 29, 2022 (CN) 202230566147.2

(51) **LOC (14) Cl.** **14-03**

(52) **U.S. Cl.**

USPC **D14/218**

(58) **Field of Classification Search**

USPC D14/218; D13/168

CPC A61G 13/101; H04B 1/406

See application file for complete search history.

(57) **CLAIM**

The ornamental design for a controller, as shown and described.

DESCRIPTION

FIG. 1 is a front perspective view of a controller, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the controller, which form no part of the claimed design.

1 Claim, 8 Drawing Sheets
